ATTORNEYS

UNITED STATES PATENT OFFICE.

HERMAN HAAS, OF MARENGO, ILLINOIS.

MUSICAL INSTRUMENT.

Application filed March 29, 1923. Serial No. 628,562.

To all whom it may concern:

Be it known that I, HERMAN HAAS, a citizen of the United States, and a resident of Marengo, in the county of McHenry and State of Illinois, have invented a new and useful Improvement in Musical Instruments, of which the following is a full, clear, and exact description.

My invention relates to improvements in musical instruments, and it consists in the combinations, constructions, and arrangements herein described and claimed.

An object of my invention is to provide a musical instrument which is adapted to be used as a toy, and which has novel means for readily changing the mechanism which actuates the key hammers, whereby the device is adapted to play any song desired.

A further object of my invention is to provide a device of the character described in which single notes may be sounded independently of each other, or a plurality of notes may be sounded in unison.

A further object of my invention is to provide a device of the character described which has a disc having a plurality of pre-arranged openings therein, and a plurality of pins which are adapted to be disposed in any of the openings desired, whereby the pins on the disc may be adjusted so as to play any piece desired.

A further object of my invention is to provide a device of the character described which has novel means for deadening the sound of the moving parts.

A further object of my invention is to provide a device of the character described which is simple in construction, durable and efficient for the purpose intended, and which is not likely to easily get out of order.

Other objects and advantages will appear in the following specification, and the novel features of the invention will be particularly pointed out in the appended claim.

My invention is illustrated in the accompanying drawings, forming part of this application, in which

Figure 1 is a plan view of the device,

Figure 2 is a side elevation of the device,

Figure 3 is a section along the line 3—3 of Figure 2, and

Figure 4 is a section along the line 4—4 of Figure 1.

In carrying out my invention, I provide a base 1 which has an upright 2, the upright being centrally disposed with respect to the

base. A disc 3 is rotatably carried by the upright 2 and is secured in place by means of a screw 4. It will be noted from Figure 1 that the disc 3 is perforated in a certain predetermined manner for a purpose herein-after described.

The mechanism for producing the sound is shown in Figures 3 and 4. It will be noted from Figure 3 that a plate 5 is carried by uprights 6 which are in turn secured to the base 1. The plate 5 has a plurality of slots 7 in which the upwardly extending ends of levers 8 are slidably disposed. The levers 8 in reality are key hammers which are adapted to strike tone producing plates 9. The levers are pivotally carried by a rod 10 which is disposed between the uprights 6. Collars 11 are disposed between the levers 8 and space the levers the desired distance 75 apart. The tone plates 9 are constructed in the same manner as the plates of a xylophone or other like instrument. It will be noted from Figure 4 that the plates 9 are supported by felt ribs 12 which in turn are disposed upon strips 13 that are secured to the base 1. A spring 14 has one of its ends secured to the upper end of each lever 8 and has its other end secured to an upwardly bent portion 15 of the plate 5. From this construction it will be noted that the levers 8 will be quickly swung into normal position when released, thereby causing the tone plates to vibrate to produce the desired notes. A stop bar 16 extends between the uprights 6 and acts as a stop for the upper portions of the levers 8. The sound ordinarily resulting from the levers striking the bars 16 is deadened by means of a felt pad 17 which is carried by the bars 16.

The means for actuating the levers 8 consists of small pins 18 which are disposed in any of the openings 19 in the disc 3 which the operator desires. The openings 19 are disposed in rings which are concentric with the axis of the disc 3. The space between each opening in one radially extending row of openings is the same as the space between the levers 8. It will therefore be apparent that the pins 18 will engage with the levers 8 when the disc 3 is rotated.

The disc 3 is rotated by means of a sprocket 20 which is rigidly mounted on a crank 21, the crank in turn being rotatably carried by a support 22 which is secured to the base 1. The teeth of the sprocket 20 are adapted to enter openings 23 in the disc

- 3, whereby the disc is rotated when the crank 21 is actuated. An idler roller 24 is rotatably carried by a bolt 25 which is secured to the support 22. The roller 24 engages with the upper surface of the disc 3 and holds the disc in engagement with the sprocket 20. The sprocket 20 and the roller 24 prevent vertical play of the disc 3 with respect to the sprocket 20.
- 10 From the foregoing description of the various parts of the device, the operation thereof may be readily understood. The pins 18 are adapted to be disposed in any of the openings 19 desired. The levers 8 each strike a different plate 9, whereby a different tone is produced by each lever. When a certain song is desired to be played by the operator, he arranges the pins in the openings 19 so as to cause the pins to engage with the levers in a predetermined manner when the disc 3 is rotated. In this way any song desired may be played by the instrument. It is obvious that more than one lever may be actuated at the same time.
- 15 20 25 It is a very simple matter to change from one tune to another tune, since the disc 3 and the pins 18 are fully exposed to view.

The device is especially adapted for use as an instructive toy, since the child has to figure out where to place the pins 18 so as to cause the device to play the right tune when actuated. The device is very simple in construction and not likely to get out of order easily.

I claim:

A musical instrument comprising a frame, a perforated disc rotatably carried by said frame, the openings in said disc being arranged in concentric circles, keys carried by said frame, tone plates carried by said frame and adapted to be set into vibration by said keys, means for yieldingly holding said keys in contact with said tone plates, deadening means for stopping the movement of said keys after said keys have struck the tone plates, and pins removably disposed in said openings, said pins having enlarged portions disposed intermediate between the ends thereof whereby either end of said pins may be inserted in the openings, said pins being adapted to move said keys when said disc is rotated whereby the device is adapted to play various tunes.

HERMAN HAAS.
